UNITED STATES PATENT OFFICE.

IRA L. SHEFFLER, OF DETROIT, MICHIGAN.

DESIGN FOR A VACUUM-CLEANER CASE.

49,864.

Specification for Design.

Patented Nov. 7, 1916.

Application filed July 17, 1916. Serial No. 109,837. Term of patent 14 years.

To all whom it may concern:

Be it known that I, IRA L. SHEFFLER, a citizen of the United States, residing at Detroit, in the county of Wayne, State of Michigan, have invented a new, original, and ornamental Design for Vacuum-Cleaner Cases, of which the following is a specification, reference being had to the accompanying drawing, forming part thereof.

The figure is a perspective view of a vacuum cleaner case, showing my new design.

Copies of this patent may be obtained for five cents each, by addressing the "Commissioner of Patents, Washington, D. C."

I claim—

The ornamental design for a vacuum cleaner case, substantially as shown.

In testimony whereof, I sign this specification in the presence of two witnesses.

IRA L. SHEFFLER.
